Primary Examiner — Kelley Donnelly

(74) Attorney, Agent, or Firm — Hubbard Johnston,
PLLC(57) **CLAIM**

The ornamental design for a drawer frame, as shown and described.

DESCRIPTION

FIG. 1 is a front perspective view of a drawer frame;
FIG. 2 is a front elevation view thereof;
FIG. 3 is a rear elevation view thereof;
FIG. 4 is a right side view thereof;
FIG. 5 is a left side view thereof;
FIG. 6 is a top plan view thereof; and,
FIG. 7 is a bottom plan view thereof.
The break lines shown in FIGS. 1, 4, 5, 6, and 7 are not part of the claimed design and represent that no particular length is claimed.
